G. M. MILLER

PADLOCK WITH NONREVERSIBLE SHACKLE

Filed April 18, 1922

UNITED STATES PATENT OFFICE.

GEORGE M. MILLER, OF LANCASTER, PENNSYLVANIA, ASSIGNOR TO FRAIM-SLAY-MAKER HARDWARE CO., INC., OF LANCASTER, PENNSYLVANIA, A CORPORATION OF PENNSYLVANIA.

PADLOCK WITH NONREVERSIBLE SHACKLE.

Application filed April 18, 1922. Serial No. 554,457.

To all whom it may concern:

Be it known that I, GEORGE M. MILLER, a citizen of the United States, residing at Lancaster, in the county of Lancaster and State 5 of Pennsylvania, have invented certain new and useful Improvements in Padlocks with Nonreversible Shackles; and I do hereby declare the following to be a full, clear, and exact description of the invention, such as 10 will enable others skilled in the art to which it appertains to make and use the same.

This invention relates to padlocks, and more particularly to a padlock especially designed and adapted to be used for locking 15 the steering wheel or the brake and gear levers of an automobile, so as to protect the owner of the machine against theft when it is left standing upon the roadside or in a public street.

20 Much trouble has been experienced by the owners of automobiles in locking the steering wheel or brake and gear levers, by inadvertently inserting the shackle in the wrong end of the lock case, and to prevent 25 this locks of the same general character as that herein described have been devised, such for instance as the lock shown in Patent No. 1,261,423 granted George M. Miller, April 2nd, 1918.

30 The object of my invention is to provide a superior lock of the same general character as that referred to but simplified and less expensive to make, consisting of few 35 parts assembled in compact form and adapted to be readily taken apart for the purpose of repairing or re-placing a worn or broken part.

The invention will first be hereinafter 40 more particularly described, with reference to the accompanying drawings, which are to be taken as a part of this specification, and then pointed out in the claims at the end of the description.

In said drawings, Fig. 1 is a side elevation 45 of a padlock embodying my invention;

Fig. 2 is a vertical sectional elevation of the same;

Fig. 3 is a vertical sectional elevation illustrating the shackle turned half-way around 50 and inserted in the casing in inoperative position and also indicating the shackle in dotted lines in the position it occupies when the attempt is made to insert it in the wrong end of the casing;

Fig. 4 is a side view of the case with the 55 near side plate removed so as to expose to view the interior locking mechanism; and

Fig. 5 is a detail cross section taken on the line 5—5 of Fig. 2.

Referring to said drawings, in which the 60 same reference characters are used to denote corresponding parts in different views, the shackle A is of U-shaped form having one of its legs longer than the other and provided with a series of notches for engagement with a spring-actuated sliding bolt or dog B arranged within the lock case C; 65 said longer leg being inserted in an opening c which extends through the case, while the short leg a is inserted in a short or blind chamber c¹ on the other side or end of the case. The bottom of the blind chamber serves as a stop to limit the inward movement of the shackle, and to permit such 70 movement to the extent required to enable the locking dog to engage the last of the series of notches in the longer leg on its inward movement, as may be necessary in making the required adjustment, the opening in which said leg is inserted extends through 75 the casing to permit the leg to pass entirely through and beyond the casing. In the form shown the locking mechanism consists of a single sliding bolt having a 80 beveled end and about midway thereof a recess or opening b therein of the peculiar 85 form shown in Fig. 5 to receive the end of a key and provide a shoulder or offset portion b¹ at one side of said recess for engagement with the key, whereby the sliding dog can be moved out of engagement with 90 the ratchet teeth or notches in the long leg of the shackle to unlock the shackle and permit it to be removed; said dog having its beveled end arranged to engage the beveled end of the notched leg so that the shackle may be readily inserted and locked at different points along its length but may be removed only when the locking dog is forcibly 95 disengaged by turning the key. The dog B is pressed toward the ratcheted limb of the shackle by means of a spring or springs D placed between an abutment or inner wall of the case and the rear end of the dog, the latter being suitably recessed 100 to receive one end of the spring or springs, which tend to normally force and hold the dog in engagement with one of the notches

in the long leg of the shackle in such manner that when the shackle is properly inserted in the case the dog will recede and engage the notches successively until the 5 shackle reaches the desired position, whereupon the dog will lock the shackle and prevent it from being removed until the dog is released by a suitable key. Between the dog and the bottom or end wall of the case 10 are placed a series of floating wards or tumblers E, having openings therethrough in alignment with the recess in the sliding dog, and adapted to be arranged in different ways so as to adapt a different key 15 to fit different arrangements of the series of tumblers, thus making it possible to use a different key for each lock. The lock case consists preferably of a metallic body of oblong form having a substantially square 20 open center and end walls of substantially semi-circular form in the concavities of which are fitted metallic tubes F and G; the tube F extending entirely through the casing while the tube G extends only part 25 way and rests upon the bottom wall or lower end of the casing, considering the other end as the upper end, thus forming a short or blind chamber to receive the short leg of the shackle, while the other tube receives the 30 longer leg. The series of tumblers are confined between plates or flanges h on a plate H, which closes one side of the opening through the center of the case, said flanges having openings therethrough in alignment 35 with the openings through the tumblers to permit the insertion of a key, the other side of said central opening being closed by a plate H¹ having openings therethrough to receive projections h¹ on the flanges h which 40 are riveted thereto or upset so as to firmly secure the two side plates together in such manner as to confine the series of wards or tumblers in proper position between said flanges. The case is provided with a key 45 guide I which is removably inserted in a hole through one end or the bottom of the case and arranged in alignment with the series of openings through the series of tumblers and the recess in the sliding dog, 50 and a key hole protector K, is pivoted to the case at one side of said key-hole so as to serve as a cover therefor and adapt it to swing toward one side to uncover said hole and permit the insertion of the key.

55 In using this lock, by reason of the short or blind chamber at one end of the casing the shackle can only be operatively inserted at that end by inserting the long leg in the opening which extends entirely through the 60 case while the short leg is inserted in the blind chamber, nor can the shackle be inserted at all in the other end of the casing, and therefore it can never be pushed down over the key-hole so as to interfere 65 with the insertion of the key, thus making

it impossible to insert and lock the shackle in the casing except in the end opposite the key-hole and rendering the lock absolutely fool-proof, and avoiding the annoyance heretofore experienced in using locks as 70 ordinarily constructed, enabling the shackle to be inserted in the wrong end of the case, thus rendering it necessary to saw off the shackle in order that it may be removed when inserted and locked in the wrong end 75 of the case.

In operation, the key is inserted in the key-hole and turned in the proper direction to cause it to engage the shouldered portion of the recess in the sliding dog, and thereby move the latter out of engagement with the notch in the long arm of the shackle so as to permit the shackle to be removed or the casing pulled off of the shackle. On removing the shackle the springs will force the sliding dog back into position to engage the notched limb of the shackle, and the shackle may be again inserted in the proper position only and withdrawn only by releasing the shackle by means of a suitable 90 key.

Having thus described my invention, what I claim as new and desire to secure by Letters Patent of the United States is:—

1. A padlock comprising a casing member 95 and a non-reversible shackle removably inserted therein together with locking means operable by inserting a key in one end of the casing, the latter having an opening therethrough at one side and a socket at the other side thereof extending parallel with said opening the greater part of its length, said socket being closed at the end thereof adjacent the exit end of said opening, and said shackle having a short leg adapted to be inserted in said socket and a long leg adapted for insertion in said opening and to protrude therethrough when said short leg reaches the closed end of said socket, said long leg being provided with a 100 series of notches adapted to be engaged by said locking means and locked in different positions.

2. A padlock comprising a case having 115 an opening which extends entirely through the case and a socket or blind chamber, a non-reversible shackle having one leg shortened for insertion in said blind chamber, the longer leg having a series of notches 120 therein and adapted in operative position to be inserted through said opening, together with locking mechanism enclosed within said case, including a sliding dog adapted to engage the notches in said long leg of the shackle and prevent its withdrawal until released by means of a key acting on said dog, and springs adapted to force said dog normally into engagement with the notches in said long leg of the 125 shackle.

3. A lock comprising a frame member having an open center and opposite side or end portions of substantially semi-circular form having their concave surfaces 5 facing said center and a tube fixed in each concavity, one tube resting upon an underlying portion of the frame member and forming therewith a blind chamber the bottom of which serves as a stop for one leg 10 of a shackle inserted in said tubes, a shackle having a long and a short leg insertible in said tubes at one end; said long leg having a series of notches therein facing the shorter leg, and locking mechanism within 15 said case including a spring-actuated sliding dog adapted to engage the notched leg of the shackle and prevent it from being withdrawn from the case until released by means of a key acting on said sliding dog.
- In testimony whereof I affix my signature 20 in the presence of two witnesses.

GEORGE M. MILLER.
